UNITED STATES PATENT OFFICE

FRANÇOIS CARTIER, OF PARIS, FRANCE

SECRET TELEGRAPHY SYSTEM

Application filed March 30, 1927, Serial No. 179,440, and in France April 23, 1926.

The present invention relates to a system of secret telegraphy and has as one of its objects to insure the secrecy of code telegrams transmitted and received by wire or wireless by converting them into signals which can not be utilized by a cryptologist for being re-converted into the original signals. The transformation is effected at the time of transmission, while the inverse operation 10 takes place on reception by means of a key strip, independently of the operator and in an automatic manner.

The following embodiment of the basic idea of the invention is given by way of example and the same refers more particularly to the Baudot five-unit code system, though it will be understood that the invention applies to any other system of the kind of transmission and reception here concerned, with 15 or without wire.

The invention, both as to its construction and mode of operation together with the objects and advantages thereof, will best be understood by reference to the following description taken in connection with the accompanying drawings, in which

Fig. 1 is a schematic diagram showing the essentials of the Baudot system of telegraphic communication;

Figs. 2 and 3 are the transmitter and the receiver, respectively, embodying the novel features of my invention;

Figs. 4 and 5 are detailed views of the keys used on keyboards U and N, respectively, shown in Fig. 2;

Fig. 6 shows a practicable embodiment of portions shown in Fig. 2;

Fig. 7 indicates the means for moving the key band or strip;

Fig. 8 is a diagrammatic illustration of a transmitter station;

Fig. 9 shows the invention as applied to radiotelegraphic transmission; and

Fig. 10 shows the invention as applied to 45 radiotelegraphic reception.

The diagram in Fig. 1 illustrates the essential elements of a Baudot telegraphic communication system. D₁ and D₂ are similar distributors which are divided into segments d₁ and d₂, respectively, the number of which is

always a multiple of five, one or two being added for synchronism. B₁ and B₂ are brushes which revolve synchronously by sliding, respectively, over segments d₁ and d₂ of distributors D₁ and D₂ in a way so as to be located always on segments of the same number. C is a keyboard comprising 5 keys T furnished with two contacts, one of which, the back contact, touches the bar P₁ connected with the positive pole of a cell, while the other, the working contact, makes contact with the bar P₂ connected with the negative pole of a cell, the keys being respectively connected to the five consecutive segments 1—2—3—4—5 of the distributor D₁. The five respective segments 1—2—3—4—5 of the distributor D₂ are connected with the five relays R₁, R₂ to R₅ of the translator S which receives and prints automatically the letters corresponding to the groups of five signals sent out by the keyboard C. There are provided as many keyboards and translators as there are groups of five segments in the distributors D₁ and D₂.

In ordinary telegraphic communication work, the two brushes B₁ and B₂ are united by the line L, L. If the different keyboards or translators are located at different stations, there is provided at each station a distributor and a friction brush, while a general line is furnished for connecting all of the brushes.

Each keyboard sends out but one letter corresponding to five signals per rotation of the distributor. The different brushes B₁ and B₂ pass successively over the segments d₁ and d₂ corresponding to the different keyboards or different translators. These arrangements are well known.

The application of the basic idea of the invention to the particular transmission system here dealt with is effected in the following manner: The sequence of 5 signals corresponding to the letters keyed at C is transformed into other sequences of five signals bearing no relationship to the former which are apt to be used by a cryptologist to remake the signals originally sent out.

(1) *Transmission.*—The transmitter device comprises essentially (see Fig. 2): two adjacent keyboards U and N the keys K and

K, of which rock between the two bars **A**₁ and **A**₂, which are united with the two poles of a cell; a group or bank of five electromagnets, the keepers of which are connected to 5 the five consecutive segments of the distributor **D**₁ and rock between the two bars **P**₁ (idle) and **P**₂ (when a current flows through the corresponding electromagnet); the bar **P**₁ is connected with the positive pole 10 of a cell **S**₁ and the bar **P**₂ with the negative pole of a cell **S**₂; and a brush **B**₁ which communicates with the line **L** and which turns uniformly while sliding over the segments of the distributor **D**₁.

15 The keys of the keyboard **U** have the diagrammatic form as indicated in Fig. 4. When idle, a spring **R** maintains contact between the key and the bar **A**₁, while when depressed it brings pressure to bear upon the 20 bar **A**₂.

The keys of the keyboard **N** have a form as shown in Fig. 5. An insulating strip **a** is placed upon the bar **A**₂, thus raising the end **m** and pressing the other end **n** upon the bar 25 **A**₁. The said insulating strip is provided with holes. When one of the latter happens to be underneath the end **m**, the key **K**₁ rocks under the action of the spring **R**₁ and comes to touch bar **A**₂, while the other end **n** ceases 30 to make contact with the bar **A**₁.

The holes of the insulating strip are separated by intervals or spaces equal to those of the keys **K**₁ of keyboard **N** in Fig. 2. They form series of 5 intervals comprising holes of 35 variable number corresponding to the signals or signs of the Baudot five-unit code.

Fig. 2 corresponds to the case where the letter **U** is manipulated upon the keyboard **U** and where the holes of the insulating strip **a** 40 correspond to the letter **N**. The diagram shows that in this case, only the second, fourth and fifth of the series of 5 electromagnets **J** are passed by currents and these cause their keepers to be pressed upon the contacts **P**₂.

45 Brush **B**, by wiping over the corresponding segments of the distributor **D**₁, will produce on the line **L** a sequence of impulses corresponding to the letter **J**. Hence, the letter 50 actually sent out differs from the one keyed at **U**, but it depends upon the letter corresponding to the holes of the insulated strip **a**, which in the present instant was for letter **N**.

55 If every time a letter is keyed at **U**, the strip is shifted in a way so as to bring a new series of holes under the keys **K**₁ of keyboard **N**, the open letter that is manipulated will 60 set up in the line **L** series of impulses corresponding to the code letters, the displacement of which with relation to the open-language letter varies constantly.

Hence, the work of coding is effected automatically with an "incoherent" key as long 65 as there are spaces between the holes on the

insulated strip, which may be called the key band or strip.

The forward travel of the latter is effected automatically upon each rotation of the brush **B**, by means of a special electromagnet **E**₁ which is actuated every time the brush passes over a segment of the distributor involved in such forward feed.

70 Fig. 6 represents a practicable disposition of the electromagnets **J** of the transmitter with their armatures or keepers **F** connected to distributor **D**₁ and contacts **P**₁ and **P**₂.

75 Fig. 7 shows in what way the forward movement of the key band or strip may be controlled by a pawl and ratchet device **P**. **a** 80 **a** is the key band rolled over the supply drum **G**, while **E**₁ is the electromagnet controlling the pawl.

85 Fig. 8 shows a diagrammatic view of the assembly of a transmitter station, **U** is the keyboard, **N**, the automatic coding keyboard, **J**, the automatic sending keyboard, **D**₁, the distributor with brush **B**₁ and the special segment **S**, **a**, the key band, and **L**, the line.

90 (2) *Receiving*.—The diagram in Fig. 8 illustrates the essential elements of the receiving apparatus used in conjunction with the transmitter illustrated in Fig. 2. **D**₂ is a distributor comprising segments and is identical to the one at the sending end, including the special segments. The brush **B**₂ turns in synchronism with the one of the transmitter so that they both pass at the same time over corresponding segments.

95 The group of five electromagnets **J**₂ controls five keys which come to make contact with **A**₂ whenever a current flows through the corresponding electromagnet, and with **A**₁ when there is no current flowing. The bank **N**₂ is analogous to bank **N** of the transmitter. The same is actuated by a key band identical to the one used in sending. The bank **U**₂ is the group of relays of the Baudot translator.

100 The circuit connections are established in the manner shown in Fig. 8. It will be seen that if the series of impulses received over the line **L**, the brush **B**₂, the segments of the distributor **D**₂ and the five electromagnets **J**₂, corresponding to the letter **J**, and if at the 105 same time to contacts **N**₂, correspond to the letter **N** which has served as a key letter in my example, the relays **U**₂ will produce in open language the letter **U** which is the one that had been keyed.

110 The forward movement of the key strip is produced at the receiving end exactly in the same way as during sending. An electromagnet **E**₂, corresponding to **E**₁ at the transmitting end is similarly connected to a special segment **S** of the distributor and controls a pawl and ratchet device diagrammatically shown in Fig. 7.

115 The safety of the cryptographic or secret system described above depends upon the 120

length of the key strip which is the only secret element of the system. This secrecy will be practically absolute as long as the number of letters of the assembly of coded

5 text does not exceed from 4 to 5 times the number of intervals of the key strip.

Key interruptions may be produced by modifying at the beginning of each message or series of messages the position of the key 10 strip, and there are as many variations or modifications of this nature as there are spaces or intervals in the key band.

It will be evident that there are a great number of possible modifications. Moreover, 15 if there is a set of numbered strips, changes of the same may be brought about, and this makes secrecy and security so much greater. The bands would then be rolled in the form of cylinders shown at G in Fig. 7 having an 20 approximate diameter of 10 centimeters.

The coding and the de-coding being accomplished automatically, the efficiency or performance of the apparatus whether of the Baudot or other type, will not be changed 25 by the addition thereto of a device as hereinbefore described.

If in Fig. 2 the line is done away with and if the brush B_1 is joined with the positive pole of the cell S_1 by way of an electromagnet 30 M (shown in Fig. 9) the system is useful for and applicable to radiotelegraphic transmission. The electromagnet M , according to whether it attracts its keeper or not, will cause the sending out of impulses or spaces, that 35 is, either working or idle waves.

The same thing holds true for reception; the working signals received by the antenna may cause the closing of the circuit of a local cell in the relay J (Fig. 10), the receiving 40 system being conveniently disposed for this object; the particular solution and means to be adopted, of course, differing according to the system of radiotelegraphy that is used.

Accidental jamming, interference, and atmospheric are able only to occasion local errors without exercising any influence upon the sequence of messages.

Having thus particularly described my invention, I claim:

50 1. In a system of telegraphic communication, a key board comprising a series of manually operated keys, a second key board having a series of automatically operated keys, a cipher strip for operating said second keys, 55 a series of electromagnets connected in series relation with corresponding keys in each of said key series, a transmitting distributor having a series of collected segments, the keepers or armatures of said electromagnets 60 being connected to a segment of each distributor, and a rotatively mounted brush connected to a line circuit for sweeping over the segments for transmitting electrical impulses resulting from the conjoint action of manual 35 and automatic keys on the electromagnets,

and additional means associated with said brush and segments for advancing said strip one step at the end of each revolution of said brush.

2. In a system of telegraphic communication, a key board comprising a series of manually operated keys for composing desired signals, a second key board having a series 70 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting 75 segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

3. In a system of telegraphic communication, a key board comprising a series of manually operated keys for composing desired signals, a second key board having a series 80 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

4. In a system of telegraphic communication, a key board comprising a series of manually operated keys for composing desired signals, a second key board having a series 85 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

5. In a system of telegraphic communication, a key board comprising a series of manually operated keys for composing desired signals, a second key board having a series 90 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

6. In a system of telegraphic communication, a key board comprising a series of manually operated keys for composing desired signals, a second key board having a series 95 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

7. In a system of telegraphic communication, a key board comprising a series of manually operated keys for composing desired signals, a second key board having a series 100 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

8. In a system of telegraphic communication, a key board comprising a series of manually operated keys for composing desired signals, a second key board having a series 105 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

9. In a system of telegraphic communication, a key board comprising a series of manually operated keys for composing desired signals, a second key board having a series 110 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

10. In a system of telegraphic communication, a key board comprising a series of manually operated keys for composing desired signals, a second key board having a series 115 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

11. In a system of telegraphic communication, a key board comprising a series of manually operated keys for composing desired signals, a second key board having a series 120 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

12. In a system of telegraphic communication, a key board comprising a series of manually operated keys for composing desired signals, a second key board having a series 125 of keys automatically operated by means of a perforated key strip, a series of electromagnets, each of said electromagnets connected in series relation with corresponding keys in each of said key series, the relative positions of corresponding keys determining the energization or de-energization of the electromagnet associated therewith, a transmitting distributor having a series of collecting segments, the keepers or armatures of said electromagnets each being connected to a segment of said distributor, a rotatively mounted brush contact connected to a line circuit for sweeping over the series of segments whereby electrical impulses, differing from the original manually-keyed signals, are transmitted, and means electrically associated with said segments and brush for advancing said strip one step at the end of each revolution of said brush.

FRANCOIS CARTIER.
